Attorney

UNITED STATES PATENT OFFICE

ISAAC HERRMANN, OF ELYRIA, OHIO, ASSIGNOR TO THE UNDERTAKERS' SUPPLY CO.,
OF CHICAGO, ILLINOIS, A CORPORATION OF ILLINOIS

HEADREST

Application filed July 18, 1928. Serial No. 293,576.

This invention relates to a head rest or support for adjustably supporting the head of an invalid or corpse and the main object of the invention is to provide a head support which may be adjusted to support the head of an invalid or corpse in any desired position. The device may be used by a surgeon or doctor to support the head of a patient while performing an operation and is also particularly adapted for use by undertakers to support the head of a corpse while preparing a body for burial.

Another object of the invention is to provide a device of the character described which comprises comparatively few parts and which is well adapted for quantity production at low cost.

Further and more limited objects of the invention will appear as the description proceeds and by reference to the accompanying drawing, in which Fig. 1 is a view in side elevation and Fig. 2 is a top plan view of the preferred embodiment of my invention.

Referring now to the drawings, the reference character 1 designates a base member which is shaped as shown most clearly in Fig. 1, the upper surface of which is provided with a plurality of notches 2. A bar 3 is pivotally connected to the base member 1 adjacent one end thereof by means of a pin 4 and extends at an angle thereto. The opposite end of the bar 3 is bifurcated as shown and pivotally secured between the bifurcations is a head rest 5 shaped to receive a human head and having a plurality of arms 6, 7 and 8. The head rest 5 is held in place by a pin 9 extending through the bifurcated end of the bar 3 and having threaded engagement therewith. The head rest 5 has a projection 10 thereon by means of which the angular position of the head rest may be adjusted without touching the head, which is a particularly desirable feature in cases of infections or contagious diseases or in cases where the device is used to support the head of a corpse where decomposition has set in.

The pin 9 has a handle 11 by means of which the pin may be turned to secure the head rest in the adjusted position. A pawl 12 is pivotally connected at one end to the

bar 3 adjacent the central portion thereof and has its opposite end adapted for engagement in the notches 2 in the base member and serves as a means for adjusting the angular position of the bar 3 with respect to the base member.

It will now be clear that I have provided an adjustable head support which will accomplish the objects of the invention as hereinbefore stated. Various changes may be made in the details of construction and manner of connecting the various parts without departing from the spirit of my invention and it is to be understood that my invention is to be limited only in accordance with the scope of the appended claims.

Having thus described my invention, what I claim is:—

1. A head support adapted to support a human head and comprising a base member, a bar having one end pivotally connected with said base member adjacent one end thereof and extending upwardly at an angle thereto, means for adjusting the position of said bar with respect to said base member, the opposite end of said bar being bifurcated, a head rest pivotally secured between the said bifurcations and shaped to receive a human head therein, a handle carried by said head rest for adjusting the position of the same and means for moving said bifurcations together whereby to secure said head rest in the adjusted position.

2. A head support comprising a supporting base including a plurality of outwardly extending foot portions connected by an elongated rigid member, a bar pivoted at one end to said base and means for positioning said bar in any one of a plurality of angular positions relative to said base, a head support secured at the other end of said bar and having three outwardly projecting arms extending from the center thereof and spaced about said center to support the head on three sides.

3. A head support comprising a supporting base including a plurality of outwardly extending foot portions connected by an elongated rigid member, a bar pivoted at one end to said base, and means for positioning said bar in any one of a plurality of angular positions relative to said base, a head support

adjustably pivoted at the free end of said bar and handle means whereby said head support may be adjusted from a distance relative to said support.

4. A head support comprising a supporting base including a plurality of outwardly extending foot portions connected by an elongated rigid member, a bar pivoted at one end to said base and means for positioning said bar in any one of a plurality of angular positions relative to said base, a head support adjustably mounted on the free end of said bar and having radially projecting arms extending laterally and endwise from the free end of said bar whereby to support the head with no obstructions beneath the same.

In testimony whereof, I hereunto affix my signature.

ISAAC HERRMANN.
